UNITED STATES PATENT OFFICE.

HENRY CLARK, OF MILWAUKEE, WIS., ASSIGNOR OF TWO-THIRDS TO FRANK W. ERBACHER AND CHRISTIAN HELMS, JR., OF SAME PLACE.

CAR-STARTER.

SPECIFICATION forming part of Letters Patent No. 280,450, dated July 3, 1883.

Application filed May 7, 1883. (No model.)

To all whom it may concern:

Be it known that I, HENRY CLARK, of Milwaukee, in the county of Milwaukee, and in the State of Wisconsin, have invented certain new and useful Improvements in Car-Starters; and I do hereby declare that the following is a full, clear, and exact description thereof.

My invention relates to devices for starting horse-cars after they have been stopped by the driver; and it consists in certain peculiarities of construction, as will be fully set forth hereinafter.

In the drawings, Figure 1 is a side elevation of a horse-car with my device attached thereto in the position it assumes when the car stops. Fig. 2 is a longitudinal section of my device, showing in full lines its position when it is in operation to start a car, and in dotted lines its position clear of the ground when the car is in motion; and Fig. 3 is a detail.

A represents the under side of a horse-car to which my device is attached, and B is a draw-bar supported in suitable bearings, *a* and *a'*, in which it has longitudinal play, and its forked front end, *b*, is adapted to receive the eye of the whiffletrees, while a stop, *b'*, prevents the said draw-bar from being pulled too far forward.

To about the center of the car-bottom and back of the rear end of the draw-bar there is secured a downward-projecting vertical elongated sheave-block, C, having sheaves *c* *c'* at top and bottom, respectively, the block being open between them to admit and form a guide for the rear arm, D, of a jointed lever, whose forward arm, D', is pivoted at *e* between the downward-projecting arms of a bracket or hanger, E, secured to the under side of the car, the inner end of one of the arms of the jointed lever being forked to receive the inner end of the other arm, and the two arms being connected by a pivot, *f*, just forward of the sheave-block, C, on which pivot is hung a shackle, F, the loop of which receives one end of a cord or chain, G, which passes back under the sheave *c'*, then up through a slot, *d*, in the arm D and over the sheave *c*, and forward to the rear end of the draw-bar B, to which it is fastened. From the lower part of the sheave-block C there extends upward a rear curved bracket,

C', which limits the drop of the arm D of the jointed lever. The forward arm, D', of the jointed lever is preferably forked in front, and each fork is curved upward and carries a weight, *d'*, at its extreme end, though the arm D' need not be forked, provided its extreme front end is weighted, as shown; and these weights are adjustable back and forth on the arm D', so as to counterbalance the weight of the rear arm, D, and its attachment, to be next described. The weights *d'* are provided with set-screws *d''*, to secure them in the required position on said arm after adjustment.

H is a block the center of which is preferably slotted to receive the rear end of the arm D, which is secured thereto by a pivot, *h*, and a flat spring, *h'*, is secured to the arm D near its rear end, the free end of said spring bearing down upon the top of the block. This block is provided with teeth *H* *H'*, which may either be directly secured to the block or form calks on a shoe secured to the block, as shown in Fig. 3.

The operation of my device will be readily understood from the foregoing description of its construction, and its advantages will be apparent to any one who has observed the difficulty experienced and expenditure of force required in again starting a horse-car which has been stopped *en route*. As long as the car is in motion the draw-bar will be pulled forward, and the jointed arms consequently in a straight line with the toothed block or starter, free from contact with the road-bed, as shown in dotted lines in Fig. 2; but when the car stops and the draft on the bar B ceases, the weights *d'* serve to draw the front end of the arm D' of the jointed lever downward and elevate the central inner ends of the arms D' D, drawing the bar B back and permitting the toothed block or shoe H to fall to the ground, as shown in Fig. 1, where the teeth *H* catch hold of the ground, and when the car is to be again started the lever D D' exerts a knee-pressure forward, the block H acting exactly like an added hind leg of a horse, and relieving the horses themselves from much exertion, and when the inertia of the wheels has been overcome and they commence to revolve, the continued shaft on the bar B instantly raises the block H from the ground.

contact with the ground, and the lever D D' resumes its horizontal position again.

Not only is my device efficacious in starting a car, but it makes a most effective brake whenever a car is stopped on an upgrade, and it is then in position for operation when the car is to be again started. Again, in case any part of the gear or harness breaks in going uphill, my device acts automatically as a brake to and prevents the car from running downhill, keeping it stationary until the damage is repaired.

Having thus described my invention, what I claim as new, and desire to secure by Letters Patent, is—

1. In a starter for horse-cars, the combination of the draw-bar B, sheave-block C, with sheaves c c', chain G, and jointed lever D D', one arm of which is weighted at its front end, while the other arm bears the toothed block H at its rear end, substantially as set forth.

2. In a starter for horse-cars, the combination of the draw-bar B and sheave-block C, with sheaves c c', and the jointed lever D D',

bearing pivoted shackle F, weights d', and 25 toothed block H, with the chain G, attached to the shackle and to the draw-bar, and passing around the sheaves and through a slot in the arm D of the lever, and the rear curved bracket, C', attached to the sheave-block to limit the 30 drop of the arm D, substantially as set forth.

3. An automatic car-starter consisting of a jointed lever, the front arm of which is weighted at its free end, and having a toothed block pivoted to the free end of the rear arm and connected with the draw-bar, as described, whereby the device is adapted to act as a brake on upgrades, and stop the car in case of breakage of gear and to be in position for starting the car again, substantially as set forth.

In testimony that I claim the foregoing I have hereunto set my hand, on this 16th day of April, 1883, in the presence of two witnesses.

HENRY CLARK.
